RLC CIRCUITS EDUCATIONAL BOARD

Douglas C. Covert, Royal Oak, Mich., assignor to
Xerox Corporation, Stamford, Conn.

Filed May 30, 1974, Ser. No. 474,493

Term of patent 14 years

Int. Cl. D19—07

U.S. Cl. D19—62

FIG. 1 is a top right front perspective view of a RLC circuits educational board showing my new design; and

FIG. 2 is a bottom left front perspective view thereof.

The rear of the educational board not shown is plain and unornamented.

I claim:

The ornamental design of an RLC circuits educational board, substantially as shown.
